DESIGN FOR A GLIDER CHAIR

Charles W. Nelems, Tarrant, Ala., assignor to
Nelems Manufacturing Company, a partnership

Application June 3, 1946, Serial No. 130,348

Term of patent 14 years

(Cl. D15—11)

To all whom it may concern:

Be it known that I, Charles W. Nelems, a citizen of the United States, residing at Tarrant, in the county of Jefferson and State of Alabama, have invented a new, original, and ornamental Design for a Glider Chair, of which the following is a specification, reference being had to the accompanying drawing, forming a part thereof.

In the drawing, the single figure is a front perspective view of a glider chair, showing my new design.

I claim:

The ornamental design for a glider chair, substantially as shown.

CHARLES W. NELEMS.
